UNITED STATES PATENT OFFICE.

JOHN J. TATUM, OF BALTIMORE, MARYLAND.

BRAKE HEAD AND SHOE.

1,119,664.

Specification of Letters Patent.

Patented Dec. 1, 1914.

Application filed April 6, 1914. Serial No. 829,905.

To all whom it may concern:

Be it known that I, JOHN J. TATUM, a citizen of the United States, residing at Baltimore, State of Maryland, have invented certain new and useful Improvements in Brake Heads and Shoes, of which the following is a specification.

It is not an uncommon incident in the operation of railroad cars to find that the key which holds the brake shoe to the brake head has become lost and the shoe dropped. The dropping of brake shoes is a source of danger as many cars are derailed by them.

To facilitate the unloading of cars they are frequently run on dumping machines and thereby turned over to discharge their freight, and in this operation shoe pins drop out of place, thereby releasing the shoe.

The object of my invention is to provide a simple but effective and economical way in which to lock the shoe pin in place against accidental displacement.

A further object of my invention is to provide a brake shoe with a combined strengthening element and key lock; and with these and minor objects in view my invention consists of the parts and combination of parts as will be fully hereinafter set forth.

In the drawings:—Figure 1 is a side elevation of a brake head and shoe embodying my invention; Fig. 2 is a side elevation of my improved brake shoe detached; Fig. 3 is a side elevation of a brake shoe showing another embodiment of my invention; Fig. 4 is a side elevation of a shoe showing another embodiment of my invention; Fig. 5 is a side elevation of a brake head and shoe showing still another embodiment of my invention.

The reference numeral 1 designates a brake head of approved construction.

The shoe 2 is composed of cast metal having embedded therein a strengthening element 3, said element being cast integral with the shoe in any approved manner. This strengthening element is provided with an end extension 4 extending in the direction of the length of the shoe, and preferably extending in a plane near the plane of the back of the shoe.

As shown in Fig. 3, I may provide the shoe with an extension at each end.

5 is the usual key for locking the shoe to

the head. After the shoe has been locked 55 to the head 1 by the key 5 as shown in Fig. 1, I bend the extension 4 over the head of the key, thereby locking the key against accidental displacement, thus exterminating all danger of derailment of the car by dropping brake shoes.

As shown in Fig. 4 I may cast a separate piece of soft metal 6 in the shoe to serve as the pin locking member. I may cast a separate piece of soft metal 7 in the brake 65 head, as shown in Fig. 5 to serve as the lock for the key.

As shown in Fig. 1, the lower end of the key 5 may be bent over to lock it in position against accidental displacement. It is a 70 well known fact that if the brake shoe becomes displaced, it permits the brake head to slip out of the hanger and allows the brake beam to fall on the tracks under the car, which usually results in an accident. 75 Such a contingency is prevented by my invention, inasmuch as the shoe cannot become accidentally displaced.

I claim:—

1. A brake shoe having an end extension 80 constructed to be turned over a brake shoe key and constitute a lock for said key.

2. A brake shoe cast with an integral soft pliable end extension adapted to be turned over a brake shoe key, when assembled, and 85 constitute a lock for said key.

3. A brake shoe composed of cast metal and a strengthening member embedded in the shoe when cast, said member projecting beyond the end of the shoe proper, the projecting portion being adapted to be bent over a brake shoe key and constitute a lock 90 therefor.

4. The combination with a brake head, and brake shoe of a pin engaging and 95 interlocking said head and shoe, and a pliable metal locking member cast integrally with one of the interlocked members and adapted to be bent over the head of the pin to lock it against accidental displacement. 100

The foregoing specification signed at Baltimore, Maryland, this 16th day of March, 1914.

JOHN J. TATUM.

In presence of—

WILLIAM E. SCHUL,

H. T. DALEY.
